Gittermann

UNITED STATES PATENT OFFICE.

SAMUEL B. DURBIN, OF TULSA, OKLAHOMA.

DEEP-WELL FISHING TOOL.

Application filed May 21, 1925. Serial No. 31,881.

To all whom it may concern:

Be it known that I, SAMUEL B. DURBIN, a citizen of the United States, residing at Tulsa, in the county of Tulsa and State of Oklahoma, have invented certain new and useful Improvements in Deep-Well Fishing Tools, of which the following is a specification, reference being had to the accompanying drawings.

This invention relates to deep well fishing tools and more particularly to a sucker rod extractor.

An important object of this invention is to provide a device of this character which is particularly adapted for removing from the well broken sections of sucker rod or tubing having a one piece slip barrel within which are arranged a plurality of sets of slips together with a single spring, the slips being so constructed that when any particular set of slips is in operation, it is urged downwardly by this single spring to its locking position.

A further object of the invention is to provide a device of this character whereby the removal of such single spring or rather of the seat against which the upper end of the spring engages will release all of the slips, thus permitting the slips to be disengaged from a rod which has been elevated from the well.

A further object of the invention is to provide a slip socket so constructed that it is readily possible to cleanly break the hold of the slips upon the engaged element.

The invention further resides in the method of constructing the slips themselves and in the details of construction of the slip socket.

Referring now more particularly to the drawings and wherein for the purpose of illustration is shown a preferred embodiment of my invention and wherein:

Figure 1 is a vertical sectional view through a fishing tool constructed in accordance with my invention showing the parts in the positions which they assume as the device is lowered into the well;

Figure 2 is a similar view illustrating one position assumed by the parts in grasping a tube or rod.

In the drawings, the numeral 10 generally designates a tube socket, the upper end of which is interiorly threaded, as at 11. Be-

low this threaded portion, the internal diameter of the socket is increased, as at 12, for a purpose presently to appear. This increase in diameter is extended through a distance slightly less than the length of the slips to be employed in the socket and below this enlarged portion, the true bore 13 of the socket tapers downwardly toward its lower end with a uniform taper. At this lower end, the bottom face of the wall is inclined outwardly and downwardly, as indicated at 14, so as to provide a funnel mouth leading to this bore. With the upper end of the tube socket is engaged a cap 15 having at its upper end means whereby it may be attached to a fishing line, as at 16, and at its lower end a threaded pin 17 for engagement in the threaded upper end 11 of the socket. The pin has a bore 18, the upper end of which has a transversely extending outlet 19 opening through the side wall of the cap. This side wall is provided with wrench squares 20 so that the cap may be readily applied and removed.

Arranged within the tapered bore 13 of the tube socket are a pair of slip units 21, 22, hereinafter referred to as the upper and lower slip units respectively. The exterior surfaces of the slips of the upper and lower units have exactly the same taper but the slips of the lower unit have less circumferential width than the slips of the upper unit so in their closely combined form, they will drop further into the reducing tapered bore 13 than the slips of the upper slip unit. The slips 23 of the lower slip unit which are preferably three in number are each formed on one vertical edge with an upwardly facing shoulder 24 and upon the opposite vertical edge with a downwardly facing shoulder 25 so that each slip has a portion overlying the next adjacent slip when they are in assembled relation. These shoulders are of sufficient breadth to prevent disengagement thereof when the lower slip unit assumes its highest position within the tapered bore, thus insuring simultaneous upward movement of all of the slips of this slip unit. The upper end of the lower slip unit is reduced to form an extension 26. The body of the slip unit has a bore 27 which tapers upwardly and each of these slips has its inner face provided with teeth for engagement with the element to be grasped.

- The reduced extension 26 has an upwardly tapered bore 28 reduced as regards the tapered bore 27 and at which the slips are likewise provided with gripping teeth.
- 5 Since the body of the lower slip unit is relatively long, it will be obvious that the toothed tapered bore thereof will accommodate several different sizes of tubes or rod, this being particularly true when it is noted
- 10 that the bore 13 tapers upwardly and accordingly as the lower slip unit moves upwardly, it will permit this slip unit to expand so that its lower end may engage a larger element that would not enter the
- 15 lower end of the bore 27 when the slip unit is in its lowermost or normal position. A size which will enter the bore at the lower end but will not pass through the upper end of the taper 27 will be engaged when
- 20 the unit is moved upwardly a slight distance to permit an expansion of the slips 23 and a corresponding enlargement of the bore 27. In other words, the operation of the slip unit is that generally provided in
- 25 the slips of such devices.
- The upper slip socket preferably likewise consists of three slips 29, these slips, however, having straight sides 30 since the escape of any of the slips of the upper unit
- 30 of the socket is prevented by the lower end slip unit 22. The lower end of the slip unit 21 has a depending skirt 31 seating upon the upwardly facing shoulder 32 formed by the reduction of the upper end of the lower
- 35 slip unit. The upper slip unit has an upwardly tapering bore 33, the lower end of which is of less diameter than the bore 28 of the reduced extension of the lower slip unit and the lower face of the units between
- 40 the upper edge of the skirt and this bore is inclined downwardly and outwardly, as indicated at 34, to provide a funnel mouth guiding a small tube or rod into the bore 33.
- 45 The upper end of the upper slip unit is externally reduced, as at 35, to thereby produce an upwardly facing shoulder 36 forming a seat for the lower end of a spring 37, the upper end of which abuts the lower end
- 50 of the pin 17 so that this spring exercises a constant pressure forcing the upper slips downwardly and through these upper slips likewise forcing the lower slips downwardly to their lowermost position. The lower slips
- 55 in their lowermost position provide a check upon the downward movement of the upper slips and the device, as it is lowered into a well, accordingly appears as in Figure 1. Assuming that the rod or tube to be grasped
- 60 is of such diameter that it must be engaged by the lower ends of the slips 23, when the device comes into engagement with the rod, the taper 14 introduces the rod into the bore
- 65 13 where it comes into engagement with the slips 23 and cause the lower slip unit 22

to move upwardly a short distance. After the rod has been fully entered in the socket, the socket is elevated and the downward movement of the lower slip unit by the spring 37 through the upper slip unit 21 70 will cause the rod to be grasped for elevation. A similar action takes place when a rod is to be engaged which may not be grasped by the toothed walls of the bore 27 but must be grasped by the walls of the 75 bore 28. In event such a rod is entered too far through the bore 28 and engages the lower face 34 of the upper slip unit, the parts will assume a position substantially as shown in Figure 2 before elevation of the 80 socket begins.

In this figure, it will be noted that while the spring no longer supplies pressure to the slip unit 22, it is supplying pressure against the upper end of the rod and it will 85 also be noted that the slips 23 are moved downwardly by gravity until the toothed walls of the bore 28 are engaged with the rod. It will be readily seen that as elevation of the tube socket takes place, the 90 movement of the rod downwardly will cause the teeth to more firmly engage and that the pressure supplied to the upper end of the rod will maintain this firm engagement during the elevation of the rod as any movements supplied to the rod once these teeth 95 come into engagement therewith is imparted to the slips of the lower unit 22. A smaller rod than those above described will, of course, pass through the lower unit, leaving 100 it undisturbed and will shift the upper unit upwardly a sufficient distance to permit this engagement. After the rod has been grasped and the device brought to the surface, by removing the cap 15, the pressure of the 105 spring upon the rods is released and the entire socket may be moved downwardly until the engaged slips are completely released from their hold upon the same.

I am aware that multiple slip sockets have 110 been produced but in all of these sockets with which I am familiar, a separate tapered bore is provided for each of the slip units and the use of a separate spring for each slip unit is also quite common. 115 This renders the structure much more difficult to produce and much more costly to maintain in operation for the severed loads and working conditions to which devices of this character are subjected apply such tremendous strains thereto that the slips are constantly wearing out and the springs thereof are broken. Accordingly, a device of this character having a very small number of parts is necessary to efficient operation. I do not claim broadly the use of 120 a slip socket having a plurality of slip units therein, but

I claim:—

1. In a deep well fishing tool, a slip socket 130

- having an elongated downwardly tapering internal bore, a plurality of separate and independently movable slip units mounted in said bore and a single spring urging all of said slip units downwardly. 5
2. In a deep well fishing tool, a slip socket having an elongated downwardly tapering internal bore, a plurality of slip units mounted in said bore and a single spring 10 urging all of said slip units downwardly, said slip units each comprising a plurality of slip sections, the slip sections of the lower units having engagement one with the other whereby engagement of one of the 15 slips of the unit causes simultaneous movement of all of the slips of the unit, the upper slip unit having at its lower end a flange seating upon the upper end of the lower slip unit. 20
3. In a deep well fishing tool, a slip socket having an elongated downwardly tapering internal bore, a plurality of slip units mounted in said bore and a single spring urging all of said slip units downwardly, 25 said slip units each comprising a plurality of slip sections, the slip sections of the lower unit having engagement one with the other whereby engagement of one of the slips of the unit causes simultaneous movement of 30 all of the slips of the unit, the upper slip unit having at its lower end a flange seating upon the upper end of the lower slip unit, the upper end of the lower slip unit having a reduced extension provided with a 35 reduced bore, said reduced extension pro-

viding a shoulder against which said flange of the upper unit seats.

4. In a deep well fishing tool, a slip socket having an elongated downwardly tapering internal bore, a plurality of slip units mounted in said bore and a single spring urging all of said slip units downwardly, the lower slip units having an upwardly tapering bore at its lower end and a reduced upwardly tapering bore at its upper 40 end and communicating with the first named bore, the upper slip unit having an upwardly tapering bore having its greatest diameter of a smaller diameter than the diameter of such reduced bore of the lower 45 slip unit.

5. In a deep well fishing tool, a slip socket having an elongated downwardly tapering internal bore, a plurality of slip units mounted in said bore and a single spring 50 urging all of said slip units downwardly, the lower slip units having an upwardly tapering bore at its lower end and a reduced upwardly tapering bore at its upper end and communicating with the first 55 named bore, the upper slip unit having an upwardly tapering bore having its greatest diameter of a smaller diameter than the diameter of such reduced bore of the lower 60 slip unit, the lower end of the upper slip unit being formed to provide a funnel mouth 65 directing a rod or pipe into the bore thereof.

In testimony whereof I hereunto affix my signature.

SAMUEL B. DURBIN.
